ELECTRICAL SWITCHING DEVICE

Harry A. Douglas, Bronson, Mich., assignor to
 Kingston Products Corporation, a corporation
 of Indiana

Application October 30, 1936, Serial No. 108,403

7 Claims. (Cl. 200—16)

This invention relates to electrical switching devices, more particularly to the type of devices suitable for use with automotive vehicles, and the principal object of this invention is to provide new and improved devices of this type.

In the drawings accompanying the specification and forming a part of this application, I have shown, for purposes of illustration, several forms which my invention may assume, and in these drawings:

Figure 1 is a vertical sectional view through an embodiment of the invention, parts being shown in elevation,

Figure 2 is a transverse sectional view corresponding substantially to the line 2—2 of figure 1, and showing, in addition, a conductor terminal adapted to cooperate with the embodiment,

Figure 3 is a perspective view, drawn to a reduced scale, showing the parts of the embodiment in disassembled relation, one of the contact means being omitted to better illustrate the housing structure,

Figure 4 is a fragmentary sectional view disclosing a different embodiment of the invention,

Figure 5 is a sectional view similar to Figure 1, but disclosing a different embodiment of the invention,

Figure 6 is a sectional view, with parts in elevation, corresponding substantially to the line 6—6 of Figure 5,

Figure 7 is a perspective view of some of the parts of the embodiment shown in Figures 5 and 6,

Figure 8 is a fragmentary sectional view similar to Figure 5, but showing a different relation of some of the parts, and

Figure 9 is a fragmentary sectional view similar to Figure 1, but showing a different relation of some of the parts.

Referring first to Figures 1 through 3, the embodiment of the invention therein disclosed comprises a bracket member 11, having a generally plane oblong surface 12, and angularly extending ears 13 adjacent the corners of the surface 12. Extending from the longitudinal margins of the bracket member 11 are flanges 14, each flange being provided with an aperture 15, for the purpose of suitably receiving a fastening means (not shown), for fastening the switching device to a mounting, which may be a portion of an automotive vehicle.

Adapted to be assembled with the bracket member 11 is a housing means 16, provided with an elongated chamber 17, the open end of which is closed by the oblong surface 12 of the bracket

11, when the parts are assembled. As shown, the housing means 16 is preferably oblong and made of a single piece of insulating material, and the upper wall, that is the wall opposite the open end, is provided with a boss 18. Each of 5 the longitudinal walls, adjacent the open end of the housing means 16, is provided with an angularly longitudinally extending flange 19, the extremities of each of the flanges 19 being notched as shown at 20. The transverse or end walls 21 10 and 22 of the housing means 16 are recessed as shown at 23 and 24 respectively. The boss 18 is provided with a pair of polygonal apertures 25, in this instance the apertures 25 being rectangular, and each aperture 25 communicates 15 with a well 26 countersinking the aperture and leading into the chamber 17 of the housing 16.

Disposed in each of the apertures 25, and the corresponding well 26, is a contact means 27. Contact means of the type preferably used are 20 fully described in a co-pending application, Serial Number 51,069, filed November 22, 1935, and only a brief description of these contact means is believed to be necessary. Each of the contact means 27 preferably comprises a sheet metal 25 tubular body 28, provided with an integral loop portion 29, ribbed as shown at 30 to strengthen the loop portion 29. The tubular body 28 is formed by bending together complementary U-shaped parts, and the extremity of the body 30 28 opposite the loop portion 29 is formed with angularly outwardly bent flanges 31. A sheet metal contact is provided to close the open end of the body 28, the contact comprising a generally annular dome-shaped portion 32, having a 35 flange at its periphery which is adapted to be clinched over the flanges 31 of the body 28, as shown at 33. A helical spring 34 and a detent member 35 are disposed within the tubular body 28 before the sheet metal contact is secured to 40 the body. The spring 34 is interposed between the detent member 35 and the inner surface of the dome-shaped portion 32, so as to urge the detent member against a shoulder formed on the body 28 adjacent the loop portion 29, and 45 also urge a portion of the detent member 35 to a position within the recess provided by the loop portion 29. A helical spring 36 is disposed about the tubular body 28 of each of the contact means 27, the spring 36 being disposed within the well 50 26, and interposed between the bottom of the well and the clinched-over extremity 33 of the sheet metal contact. It will be appreciated that the body 28 of each contact means 27 is provided with a transverse section to fit the aper- 55

ture 25 so that the contact means is held against rotation.

An actuating member 37, preferably made of sheet metal as shown, is adapted to move through the chamber 17 of the housing means 16, the actuating member 37 having a tubular portion 38 provided with a closed end 39, and also having a trough-like U-shaped portion 40, the vertical walls of which (Figure 3) being beveled at one end as shown at 41, and adjacent this end, the transverse or bight wall is provided with an aperture 42, which is adapted to receive fastening means for fastening the actuating member 37 to a mechanism (not shown) for effecting movement of the actuating member 37. As best shown in Figure 3, the vertical walls of the trough portion 40 are provided with extensions 43, forming recesses 44 with the tubular portion 38, and also forming abutting walls 45.

20 Detachably mounted on the actuating member 37 is a carrier block 46 preferably formed of insulating material, and being generally oblong in shape. The top surface of the carrier block is provided with a step formation, forming an elongated undercut surface 47. The longitudinal margins of the carrier block 46 are recessed as shown at 48, and the under-surface of the carrier block 46 is provided with a longitudinally extending arcuate groove 49. Extending transversely of the carrier block 46 is a recess 50, providing transversely extending lug portions 51 and 52, and as shown, the lug portion 52 is of a greater longitudinal length than the lug portion 51. The lug portion 51 is constructed and arranged to closely fit within the recesses 44 of the actuating member 37, the transverse recess 50 being of a length substantially equal to the length of the extensions 43, so that the lug portion 52 has its inner surface engaging the abutting walls 45, thereby providing only one predetermined position in which the carrier block 46 may be assembled with the actuating means 37. Of course, it will be understood that the lug portions 51 and 52, and the recess 50 may be so constructed that the carrier block 46 may be assembled with the actuating means 37 in two positions.

Bridge means 53 are adapted to be assembled with the carrier block 46, and as best shown in Figure 3, the bridge means 53 comprises a generally oblong current conducting plate 54 of a transverse size slightly less than the width of the carrier block 46, and of a longitudinal length substantially equal to the under-cut surface 47. The plate 54 is provided with angularly extending ears 55 adapted to be received in the recesses 48 provided in the longitudinal margins of the carrier block 46.

The parts of the switching device may be assembled in any desirable manner, and when assembled, the carrier block 46 carrying the bridge means 53 is properly positioned on the actuating member 37 as shown in Figures 1 and 2, and the bottom surface of the actuating member 37 is slidably supported by the elongated plane surface 12. The arcuate groove 49 formed in the carrier block 46, provides space for a resilient means, such as the helical spring 56, the latter being disposed within the confines of the actuating member 37, and having one extremity bearing against the closed end 39 of the tubular portion 38, and its other extremity bearing against the transverse wall 21 of the housing means 16. As shown in Figure 1, the wall 21 is made somewhat thicker than the wall 22, so that the force exerted by the spring 56 will not fracture the

wall 21. It will be appreciated that the recesses 23 and 24, formed in the transverse walls of the housing means 16, are preferably shaped to respectively accommodate the tubular portion 38 and the trough-like portion 40 of the actuating member 37. The contact means 27, after proper assembly, are urged inwardly of the elongated chamber 17, so that the contact of each contact means is pressed into engagement with either the bridge means 53 or the top surface of the carrier block 46. The housing means 16 is suitably secured to the bracket member 11 by clinching the extremities of the ears 13 over the upper surface of the longitudinal flanges 19, as best shown in Figure 2, it being appreciated that the fingers 13 fit in the notched portions 20 of the housing means 16.

Referring again to Figure 2, it will be obvious that the chamber 17 of the housing means 16 is just slightly wider than the width of the carrier block 46, so that the walls of the chamber 17 more or less position the carrier block 46 laterally with respect to the actuating member 37.

A plug conductor 57, of the snap type, is shown in Figure 2 ready to be assembled with the loop portion 29 of one of the contact means 27. The plug conductor 57 is provided with a tapered nose and an annular furrow, the tapered nose being provided with swaging indentations for holding the current conducting portion of an electrical conductor. To assemble the plug conductor 57 with the contact means 27, the tapered nose is inserted into the recess provided by the loop portion 29, such insertion causing the detent means to be moved inwardly of the tubular body 28 until the annular furrow is brought into alignment with the detent means, whereupon the detent means snaps into the annular furrow to resiliently hold the plug conductor 57 in electrical and mechanical engagement with the contact means 27.

Assuming that the parts have been properly assembled, and referring particularly to Figure 1, it will be noted that the bridge means 53 engages only one of the contact means 27, and therefore 45 electrical circuit between the two contact means shown is broken. To establish electrical circuit between the two contact means 27, the actuating member 37 is pulled to the right, against the action of the spring 56, this movement being 50 limited by abutment of the adjacent end of the carrier block 46 with the inner surface of the lateral wall 21. When the actuating member 37 has been moved a sufficient distance to the right, the bridge means 53 engages both of the contact 55 means 27 and completes an electrical circuit therethrough. As soon as the force holding the actuating member 37 in its "on" or right-hand position is removed, the spring 56 urges the actuating member 37, the carrier block 46, and bridge means 60 53 carried thereby, to the "off" position shown in Figure 1, movement in this direction being limited by abutment of the adjacent surface of the carrier block 46 with the inner surface of the lateral wall 22 of the housing means 16. Therefore it will be obvious that the switching device 65 is normally held in an "off" position, but may be moved to an "on" position by force overcoming the action of the spring 56. It will be obvious to those skilled in the art, that the actuating member 37 may be constructed and arranged to carry more than one carrier block and bridge means, so as to provide switch means for a series of contact means which may be carried by the housing means 16.

Referring to Figure 4, the embodiment therein shown comprises a structure quite similar to the embodiment shown in Figures 1 through 3, and like parts will be given like numbers supplemented by the subscript *a*. As shown in this embodiment, the housing means **16a** is provided with an opening **24a** in the transverse wall **22a**, the aperture **24a** accommodating the tubular portion **38a** of the actuating member **37a**. However, in this embodiment the opposite vertical walls of the trough portion **40a** are provided with lateral extensions **58**, preferably struck-out from the vertical walls, the extensions being constructed and arranged so as to engage the inner surface of the transverse wall **22a**, and thereby limit movement of the actuating member **37a** before the adjacent surface of the carrier block **46a** abuts the interior surface of the transverse wall **22a**. With this construction, it will be obvious that strain produced by the urging force of the spring **56a** will be taken up by the lateral extensions **58**, instead of by the carrier block **46a**.

Referring to Figures 5 through 7, the embodiment of the invention therein shown comprises a bracket member **60** having an elongated generally plane surface **61**, provided with a centrally located longitudinal groove **62** intermediate the ends of the bracket member **60**, the ends being provided with arcuate bearing surfaces **63**. As before, the bracket member **60** is provided with extending fingers **64** and laterally extending flanges **65**.

A housing means **66** is preferably formed of a single piece of insulating material, and is adapted to be secured to the bracket member **60**, by clinching the extremities of the fingers **64** over longitudinally extending flanges formed on the housing means **66**. The transverse ends of the housing means **66** are provided with arcuate slots **67**, to provide for reciprocal movement of an actuating member **68**, the surfaces **63** of the bracket member **60** providing bearing surfaces for the actuating member **68**, and cooperating with the slots **67** to substantially close the chamber formed within the housing means **66**. The actuating member **68**, as here shown, comprises a solid cylindrical rod, having one extremity flattened as at **69** and provided at this extremity with an aperture **70** adapted to receive a fastening means leading to mechanism (not shown) for effecting movement of the actuating member **68**. Spaced inwardly from its other extremity, the actuating member **68** is provided with diametrically opposed slots **71**, for receiving a spring clip **72**, a washer **73** being slipped onto the actuating member **68** before the spring-clip **72** is sprung into position, as best shown in Figure 5.

A carrier block **74** is mounted on the actuating member **68**, and has a longitudinally extending arcuate groove **75** in its lower surface, the groove **75** being interrupted by a web portion **76**, which latter portion has an aperture **77** for receiving the actuating member **68**. The groove **75** is extended to provide a recess for accommodating the washer **73** and the spring member **72**. As best shown in Figure 5, the washer **73** abuts one side of the web **76**, and resilient means, such as a helical spring **78** disposed about the actuating member **68**, has its one end bearing against the other side of the web **76**, and the other end of the spring **78** bears against the inside surface of the transverse wall of the housing means **66**. It will be obvious, in view of the foregoing, that the actuating member **68** and the carrier block **74** will be

urged to the left, as shown in Figure 5. Movement of the actuating member **68** to the right will cause movement of the carrier block **74** against the action of the spring **78**. The clip member **72** has been arranged with respect to the actuating member **68**, so as to abut the adjacent surface of the transverse wall of the housing means **66**, before the carrier block **74** abuts this surface, so as to limit movement of the actuating member **68** to the left.

As best shown in Figure 7, bridge means **79** are adapted to be assembled with the carrier block **74**, the bridge means **79** comprising the generally elongated current conducting plate having fingers **80** extending angularly from the transverse margins of the plate. The carrier block **74** has its top surface undercut a sufficient amount so that the bridge means **79** may be placed in the undercut portion, and have its outer surface in flush relation with the top surface of the remaining portion of the carrier block **74**. The carrier block **74** is provided with recesses **81** adapted to receive the fingers **80** formed on the bridge means **79**.

Contact means **82**, similar to the contact means **27** hereinbefore described, are mounted on the housing means **66** for cooperation with the bridge means **79**, and as best shown in Figure 5, the bridge means and the carrier block **74** are mounted on the actuating member **68**, so that the bridge means **79** normally engages the contacts of both of the contact means **82**, and thereby places these contact means in electrical circuit. When the actuating member **68** is pulled to the right, (Figure 5) the bridge means **79** engages the contact of only one contact means **82**, and electrical circuit between the contact means is broken.

Referring particularly to Figure 6, it will be noted that the chamber portion of the housing means **66** is of a width to closely accommodate the lateral width of the carrier block **74**, and the bottom surface of the carrier block rides on the generally plane portion **61** of the bracket member **60**. The arcuate groove **62** slidably engages the rounded extremity of the web **76** to guide movement of the carrier block **74**, the groove **62** also providing a recess for accommodating the spring **78**.

The construction shown in Figure 8 discloses a different relation of the parts comprising the embodiment disclosed in Figures 5 through 7, the parts being somewhat similar to the parts hereinbefore described, and like numerals bearing the subscript *c* will designate like parts. In this construction, the bridge means **79c**, in the normal position of the switch, that is, the position wherein the spring **78c** normally maintains the actuating member **68c** and the carrier block **74c** in the left-hand position, engages only one of the contact means **82c**, and therefore the circuit between the two contact means **82c** is normally broken. Movement of the actuating member **68c** to the right, causes the bridge means **79c** to engage both of the contact means **82c**, and thereby establishes circuit between the contact means. It will be obvious that the carrier block **74c** will have its upper surface undercut at the proper location so as to accommodate the bridge means **79c**.

Referring to Figure 9, the construction therein shown is somewhat similar to the construction shown in Figures 1 through 3, and like numerals bearing the subscript *d* will designate like parts. In the construction shown in Figure 9, the bridge means **53d** normally engages both of the contact

means 27d, when the actuating member 31d is in its normal or left-hand position, so that the contact means 27d are in electrical circuit. Movement of the actuating member 31d to the right will cause the bridge means 53d to disengage one of the contact means 27d, and thereby interrupt electrical circuit between the contact means 27d. Again, the carrier block 46d will be provided with an undercut top surface to properly accommodate the bridge means 53d.

It will be apparent to those skilled in the art that I have accomplished at least the principal object of my invention, and it also will be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto.

I claim:

1. An electric switch, comprising: a casing, having a supporting wall, and walls extending angularly from the marginal surface of said supporting wall, certain opposite extending walls being recessed; a first switch element, carried by said supporting wall; a second switch element, disposed within the chamber formed by said casing, and being movable relative to said first switch element; generally tubular actuating means, extending through said casing, and having its extremities projecting through the recesses in said extending walls, said actuating means being connected to said movable switch element, and constructed and arranged to move said movable element to different positions with respect to said stationary element; spring means, disposed within the confines of said tubular actuating means, and having one end bearing against a part of said actuating means at one extremity of said actuating means, and the other end bearing against the extending wall through which the opposite extremity of said actuating means projects, said spring means being constructed and arranged to urge said movable switch element to a predetermined relation with respect to said first switch element; and plate means, spanning the terminating margins of said angularly extending walls to close off said casing, said plate means being secured to said casing.

2. An electric switch, comprising: a casing, having a supporting wall, and walls extending angularly from the marginal surface of said supporting wall, certain opposite extending walls being recessed; a first switch element, carried by said supporting wall; a second switch element having a carrier therefor, disposed within the chamber formed by said casing, and being movable relative to said first switch element; metal actuating means, having a portion within the casing connected to said carrier, and having its extremities slidably extending through the apertures in said certain extending walls, said actuating means being assemblable with said recesses by movement in a direction transverse to the axis of said actuating means, and said actuating means including an elongated rectilinear surface intermediate its extremities; and closure means, secured to said angularly extending walls, and having an elongated rectilinear surface constructed and arranged for cooperation with said surface of said actuating means, to provide a bearing surface for said actuating member.

3. An electric switch, comprising: an open-sided casing, formed of insulating material, the closed-side wall and end walls providing an elongated space, said close-side wall having an aperture countersunk by a recess leading into said space, and opposite end walls having notches extending inwardly from the marginal surfaces of these end walls; actuating means, comprising an elongated member reciprocable through the notches in said end walls; a carrier; bridge means secured to said carrier, carried by that portion of the actuating means within said space; a terminal post, extending through said aperture, and having a contact head at one extremity disposed within said space, and means adjacent its other extremity for resiliently retaining a terminal, said terminal post being bodily reciprocable through said aperture in a direction transverse to the movement of said bridge means; and resilient means, constructed and arranged to urge said contact head into engagement with said bridge means.

4. An electric switch, comprising: an open-sided casing, formed of insulating material, the closed-side wall and end walls providing an elongated space, said closed-side wall having an aperture countersunk by a recess leading into said space, and opposite end walls having notches extending inwardly from the marginal surfaces of these end walls; actuating means, comprising an elongated member reciprocable through the notches in said end walls; a carrier; bridge means secured to said carrier; said carrier being carried by that portion of the actuating means within said space; a terminal post, extending through said aperture, and having a contact head at one extremity disposed within said space, and means adjacent its other extremity for resiliently retaining a terminal, said terminal post being bodily reciprocable through said aperture in a direction transverse to the movement of said bridge means; plate means, spanning the marginal surfaces of said end wall, and secured to said casing for closing off said space; and resilient means, constructed and arranged to urge said contact head into engagement with said bridge means, the urging force of said resilient means being transmitted through said bridge means, urging said actuating means to bearing relation with respect to a portion of said plate means.

5. An electric switch, comprising: an open-sided casing, the closed-side wall and the end walls depending from the closed-side wall forming a space, certain opposite end walls having notches extending inwardly from the marginal surfaces of these end walls; contact means, carried by said closed-side wall, having a contact head extending into said space; a carrier; bridge means, secured to said carrier disposed within said space, for movement into and out of engagement with said contact head; plate means, secured to said casing in position spanning the marginal surfaces of said end walls, and closing off said space; and metal actuating means, having portions closely but slidably fitting through notches in respective end walls, and having also a portion within said casing connected to said carrier for effecting movement of said bridge means; said plate means holding the portions in said notches, and providing a bearing surface along which said actuating means slides.

6. An electric switch, comprising: an open-sided casing, the closed-side wall and the end

5

10

15

20

walls depending from the closed-side wall forming a space, certain of the end walls being formed with abutment means; contact means, carried by said closed-side wall, having a contact head extending into said space; a carrier; bridge means secured to said carrier, disposed within said space, for movement into and out of engagement with said contact head; metal actuating means, reciprocably mounted with respect to said casing, having a portion within said casing connected to said carrier for effecting movement of said bridge means; and plate means, spanning the terminating margins of said end walls, and having tongue means bent to overlie a surface of the abutment means formed on said end walls, thereby to hold said plate means to said casing.

7. An electrical switch, comprising: a casing, having a supporting wall, and walls extending angularly from the marginal surface of said supporting wall, certain opposite extending walls being recessed; a first switch element, carried by said supporting wall; a second switch ele-

ment, disposed within the chamber formed by said casing, and being movable relative to said first switch element; actuating means, extending through said casing, and having its extremities projecting through the recesses in said extending walls, said actuating means being connected to said movable switch element, and constructed and arranged to move said movable element to different positions with respect to said stationary element; spring means, carried by said actuating means, and having one end bearing against an abutment associated with one extremity of said actuating means, and the other end bearing against the extending wall through which the opposite extremity of said actuating means projects, said spring means being constructed and arranged to move said movable switch element to a predetermined relation with respect to said first switch element; and plate means, spanning the terminating margins of said angularly extending walls to close off said casing, said plate means being secured to said casing.

HARRY A. DOUGLAS.
